RADIANT AND CONVECTION
SUPERHEATERWilbur H. Armacost, New York, N. Y., assignor
to The Superheater Company, New York,
N. Y.Application September 29, 1931, Serial No. 565,793
Renewed February 17, 1934

3 Claims. (Cl. 122—479)

My invention relates to superheater boilers and aims to provide an arrangement whereby a high constant superheat may be obtained without endangering any of the superheater elements.

- 5 It is common practice to build the superheater for a boiler so as to utilize heat from the boiler furnace. Since, however, the fire in the furnace cannot always be regulated in exact proportion to the draft of steam from the boiler, the metal of
10 the superheater elements may sometimes become overheated to such an extent as to materially shorten the life of such elements. Furthermore, a superheater built into a boiler in a given location does not yield ordinarily a constant tempera-
15 ture at different loads or rates of steam flow even when the fire is regulated carefully in proportion to the steam flow. In other words, the ordinary superheater boiler has either a rising or a falling temperature characteristic.
20 It is the object of my invention to provide a novel arrangement whereby the temperature of steam delivered by a superheater boiler may be maintained substantially constant over a wide range of load, while at the same time radiant
25 superheater elements used with such boiler may be protected from overheating.
The novel features of my invention are pointed out in the appended claims. The invention itself, however, together with its objects and advan-
30 tages, will best be understood from a detail description, taken in connection with the accom-
panying drawings, of several arrangements of superheater and boiler selected by way of example from a number of possible embodiments of the
35 invention. In said drawings,

Fig. 1 is an elevation, partly in section, of a superheater boiler in accordance with the invention.

Fig. 2 is a diagrammatic view illustrating the 40 method of operation of the apparatus shown in Fig. 2.

Figs. 3, 4 and 5 are diagrammatic views illustrating additional superheater arrangements within the invention.

- 45 In the arrangement illustrated in Fig. 1 there is a boiler 10 having a slag screen bank 12 and an upper generating bank 14 together with the usual steam drum 16. Between the banks 12 and 14 is a convection type superheater 18. Steam for the
50 superheater 18 is taken off the drum 16 through a pipe 20 which delivers to an inlet header 22. The steam pipe 20 is, moreover, extended beyond the header 22 by branch 21 so as to deliver to an inlet header 24 of a radiant type superheater 26.
55 Steam passes from the header 22 through the ele-
ments of superheater 18 into an outlet header 28 which delivers into a branch outlet pipe 30. Similarly the steam from header 24 passes through elements of superheater 26 into an outlet header 29 and thence thru a branch conduit 31 to a point 60 32 at which branches 30 and 31 unite in a main steam delivery pipe 34 for superheated steam. It will be seen therefore that superheaters 18 and 26 are connected so that steam from the boiler 10 passes through them in parallel. It is assumed 65 moreover that, in the apparatus of Fig. 1, the steam will divide equally between the two superheaters. The parts can readily be designed to accomplish this. Moreover, it is assumed that the superheaters 18 and 26 are so designed that, 70 when each is passing one-half the steam flow at full load and with normal fire in the furnace 11, the temperature at the outlet of each of the superheaters 18 and 26 will be such that the tempera-
75 ture at the inlet of pipe 34 will be that desired. 75 As convection type superheaters such as 18 have ordinarily a rising temperature characteristic with increase of load and radiant type superheaters such as 26 have ordinarily a falling tempera-
80 ture characteristic with increase of load, the 80 temperature at the intake of pipe 34 will remain substantially constant with changes in load. I do not limit myself to such proportions of superheaters 18 and 26. However, the radiant type superheater 26 often receives almost as much heat 85 at times of low load on boiler 10 as at times of high load so that there may be danger of overheating the metal in its elements.

To avoid this difficulty, I have illustrated herein a means whereby a greater proportion of the 90 steam flow may be caused ordinarily to pass through superheater 26. For this purpose a thermo-couple 36 is placed in pipe 31 near the outlet of superheater 26 and a thermo couple 38 is placed in pipe 30 near the outlet of superheater 18. The 95 wires 37 from the thermo-couple 36 and the wires 39 from the thermo-couple 38 are conducted to a relay contained in box 40 and there employed to operate relay means controlling the circuit of the motor in the casing 42 which is arranged to 100 operate butterfly valve 44 near the inlet of radi-
ant superheater 26 for controlling the flow of steam thereto. As the temperature at the thermo-couple 36 increases relative to that of thermo-couple 38, valve 44 is operated in a man-
105 ner well understood by those skilled in the art to admit a greater proportion of the steam flow to superheater 26. In order to accentuate the action of valve 44 I prefer to place cooperating means in pipe 30 also. In Fig. 1 I have illustrated 110

such means in the form of an orifice plate 46 adapted to create a slight drop in pressure of the steam in passing through the orifice so that there is normally some back pressure on the 5 superheater 18 available to force an additional amount of steam through the superheater 26 as the valve 44 is opened more widely.

Fig. 2 is merely a diagrammatic showing of the apparatus shown in Fig. 1 to make the method 10 of operation more plain.

Fig. 3 is a diagrammatic illustration of an apparatus similar in most respects to that shown in Figs. 1 and 2, but in which a valve 48 is placed in the intake line of the convection type superheater 15 18 to assist the valve 44 in controlling the relative proportion of steam flowing into the superheaters. In Fig. 3, the orifice plate 46 is dispensed with, its function being carried out by butterfly valve 48. It will be seen that, in the 20 arrangement shown in Fig. 3, the valve 44 has a lever 50 fixed to its spindle and connected to a lever 52 on the spindle of valve 48 by a rod 54 so that valves 44 and 48 may both be operated by the same motor in the casing 42. It will be 25 seen, moreover, from Fig. 3 that valves 44 and 48 are set to work oppositely, valve 48 being nearly closed at the time valve 44 is wide open.

In the arrangement illustrated in Fig. 4, a single flap valve 56 is placed at the junction point 30 32 and so operated by a motor in the casing 42b as to control the relative flow through the superheaters 18 and 26 by choking more or less the outlet of either the conduit 30 or the conduit 31 depending on which way the valve is turned from 35 its central position. The motor in box 42b will be understood to be controlled by the relay box 40 which is controlled in turn by the thermo-couples 36 and 48, as described above in connection with Fig. 1. In other respects, the arrangement shown in Fig. 4 is so similar to that of Figs. 40 2 and 3 that it needs no further description.

Fig. 5 illustrates diagrammatically an arrangement in which separate motors contained in casings 42a and 42c control the valves 44 and 48 45 in response to the relay mechanism in box 40. The separate motor in casing 42c is provided in this arrangement in order that valve 48 may be controlled independently of the thermo-couples 36 and 38 when desired, and for this purpose a second relay mechanism is provided in a box 44 which is controlled by a push button 58. It will be understood therefore that by pushing the button 58 the operator may control the valve 48 to substantially cut off the flow through the convection superheater 18, irrespective of the action of 50 couples 36 and 38. This may be desirable at times when the boiler is being started up as the fire at this time is often brought up rapidly so that the radiant superheater is exposed to high temperature. On the other hand, the convection type superheater 18 is protected by the generating tubes at such times for the reason that they are cooler than normal until the boiler pressure has 55 been brought up to that of the line. During starting, however, special means may be used to provide a flow of steam through superheater 26 and in such case relay box 41 and push button 58 may be omitted.

In each of Figs. 2, 3, 4 and 5, I have shown one 60 of the thermo couples at the outlet of the convection superheater. I do not limit myself to

this, however, as one of the thermo couples may be omitted. If only one thermo-couple is used it may be in pipe 31. When two are employed, one may be in line 34 adjacent the junction point 80 32. Furthermore, I do not limit myself to thermo-couples, since other suitable thermostatic means are known which may be substituted for thermo-couples in the arrangement for controlling the proportion of the total steam flow passing through the radiant superheater.

While it is assumed that superheaters 18 and 26 in the arrangements described above have such proportions and are so arranged as to give the same degree of superheat at their outlets at normal full load, I do not limit myself to this. Whether or not the two superheaters are designed to give the same temperature, the means for increasing the proportional flow through one superheater or the other comes into play when the temperatures at the outlets of the superheaters change only slightly from those predetermined by the designer to thereby cause a difference between the temperatures at such outlets or increasing the difference in temperature beyond that intended.

What I claim is:

1. The combination of a boiler, a furnace therefor, a radiant and a convection type superheater arranged to utilize heat from said boiler and connected to the boiler so that the steam flow in one is parallel to that in the other, said superheaters having relative proportions and positions such that the desired total superheat is attained in the neighborhood of normal full load and when the steam flows in them are equal means for diverting a greater or lesser portion of the total steam flow through one superheater or the other, and means for controlling said means to increase the proportion of steam flowing through the radiant superheater in response to increase in temperature of steam at its outlet.

2. The combination of a boiler, a furnace therefor, a radiant and a convection type superheater arranged to utilize heat from said furnace and so connected to said boiler that the steam flow in one is parallel to that in the other, said superheaters having relative proportions and positions such that the desired total superheat is attained in the neighborhood of normal full load and when the steam flows in them are equal means for diverting a greater portion of the total steam flow through the radiant superheater when the temperature at the outlet of the radiant superheater is greater than that at the outlet of the convection superheater.

3. The combination of a boiler, a furnace therefor, a radiant and convection type superheater arranged to utilize heat from said furnace and connected to said boiler so that steam flow in one is parallel to that in the other, said superheaters having relative proportions and positions such that the desired total superheat is attained in the neighborhood of normal full load and when the steam flows in them are equal means for diverting a greater or lesser portion of the steam flow through one superheater or the other, and means for controlling said means to maintain the steam temperatures substantially equal at the outlets of the two superheaters.
